UNITED STATES PATENT OFFICE.

JOHN N. COLBY, OF BOSTON, MASSACHUSETTS, ASSIGNOR OF TWO-THIRDS TO LOUIS ENGLEHARDT, OF SAME PLACE, AND ARTHUR LAWRENCE, OF WINTHROP, MASSACHUSETTS.

GRATING-MACHINE.

SPECIFICATION forming part of Letters Patent No. 439,930, dated November 4, 1890.

Application filed April 8, 1890. Serial No. 347,030. (No model.)

To all whom it may concern:

Be it known that I, JOHN N. COLBY, of Boston, in the county of Suffolk, State of Massachusetts, have invented certain new and useful Improvements in Grating-Machines, of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved grater. Fig. 2 is an end elevation of the same, looking from the left in Fig. 1; and Fig. 3, sectional views illustrating certain details of construction.

Like letters of reference indicate corresponding parts in the different figures of the drawings.

My invention relates especially to a device for grating lemons, fruits, vegetables, &c., for cooking purposes; and it consists in certain novel features hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the clamp and B the grinding-disk. The clamp is U-shaped to adapt it to fit over the edge of a table or stand C, and is provided with a set-screw b for holding it in position thereon. The upper end of the clamp is forked, forming two arms d, in which is journaled a horizontally-arranged worm f. The grinding-disk B is secured to one end of said worm and is provided with a handle g for rotating it. The inner face of the disk is "pricked up," or provided with sharp projections or teeth h, as shown in Fig. 2, for tearing away the body of the lemon, said teeth being formed on a plate i, secured to said disk, as shown in Fig. 1. A horizontally-arranged cylinder D, open at both ends, is secured to an arm d by means

of a screw j, one end thereof being in close proximity to the roughened face of the disk B, 50 as best shown in Fig. 1. A screw j passes through a slot k in the arm d, whereby the position of said cylinder in relation to the face of the disk B may be detached.

The cylinder D is provided with a longitudinal slot m. A nut p is fitted to slide loosely on the worm f. Pawls q are pivoted at t in the nut p, at opposite sides of the worm f, said pawls having a threaded head v, (see Fig. 3,) adapted to mesh with the threads of 60 said screw. Flatsprings w, secured to the nut with their free end in engagement with the long arms of said pawls tend to hold said threaded heads in engagement with said worm. An arm x is secured to the nut p and projects 65 through the slot m into the cylinder D. Flanges y are formed on said arm and engage the walls of the cylinder, said flanges serving as guides to prevent the arm from binding in said slot. A vertically-arranged disk z, fitted 70 to slide easily in the cylinder, is secured to the inner end of the arm x by brazing or other suitable means, said arm and disk forming a plunger for forcing the fruit through said cylinder against the grating-disk.

In the use of my improvement, the long arms of the pawls q being depressed, the nut p may readily be moved from right to left on the worm f, withdrawing thereby the disk z from the cylinder D. A lemon or other article to 80 be grated is inserted in said cylinder and the plunger brought forward into contact therewith. The pawls being released, their threaded heads v are meshed with the worm f. By rotating the disk B said worm is set in motion 85 and the nut p caused to travel thereon from left to right, the disk z attached thereto forcing the lemon in the cylinder against the face i on the disk B. The teeth or projections h on said disk attacking the lemon grinds or 90 pulverizes it evenly, the product thus formed falling through the space between the disk and the adjacent end of the cylinder D into a receptacle on the table C. It will be seen that as the disk B is rotated, driving the worm f, the 95 nut p is conjointly driven thereby on said

worm and the lemon or other substance in the cylinder continuously forced against the grinding-disk until it is thoroughly pulverized.

When constructed as described, the operation of the device is exceedingly rapid and the parts so formed that they may be very readily separated or detached for cleaning.

The device is equally well adapted for grinding chocolate, nutmegs, and articles of similar nature.

Having thus explained my invention, what I claim is—

1. The combination of a worm journaled in a standard, a grinding-disk thereon, a cylinder secured to said standard, and a nut fitted to travel on said worm, said nut carrying a plunger sliding in said cylinder, substantially as described.
2. In a grater, the combination of a clamp, a horizontal worm journaled thereon and bearing a grater-disk, a nut fitted to slide on said worm and provided with a threaded lever for causing it to work thereon, a horizontal cylinder on the clamp, and a plunger secured to the nut, substantially as described.
3. In a grating-machine, the clamp A and worm f, journaled therein, in combination with the grating-disk B, cylinder D, having the slot m, and the nut p, bearing the plunger-disk z, substantially as described.
4. In a grater, the combination of a clamp,

a worm, a rotary disk thereon, a cylinder opening against said disk, and a nut traveling on the worm and bearing a plunger working in the cylinder, substantially as described.

35

5. In a grater, the combination of a worm bearing a rotary grating-disk, with a slotted cylinder on the worm-support and a nut bearing a plunger working in said cylinder, said nut being fitted to slide freely on the worm and provided with spring-cushioned toothed pawls meshing therewith.

6. In a grater, the worm f, journaled in the clamp A and bearing the disk B, in combination with the slotted cylinder D, the nut p, having toothed pawls q, and the plunger z on said nut, substantially as described.

7. In a grater, a forked clamp, a worm journaled in the arms thereof, a grating-disk on said worm, a slotted cylinder secured to the clamp and opening against said disk, a nut fitted to slide on said worm and bearing a plunger-disk working in said cylinder, and spring-pawls pivoted in said nut, said pawls having toothed heads meshing with the worm, whereby the nut may be caused to travel thereon, substantially as described.

JOHN N. COLBY.
